ASSIGNORS TO CROMPTON & KNOWLES LOOM WORKS, A CORPORATION OF MASSA-
CHUSETTS.

FILLING-THREAD-CUTTING MECHANISM FOR WEFT-REPLENISHING LOOMS.

1,070,979.

Specification of Letters Patent.

Patented Aug. 19, 1913.

Application filed January 18, 1912. Serial No. 671,966.

To all whom it may concern:

Be it known that we, ALFRED F. MORELL and ALBERT A. GORDON, Jr., citizens of the United States, both residing at Worcester, 5 in the county of Worcester and State of Massachusetts, have jointly invented certain new and useful Improvements in Filling-Thread-Cutting Mechanism for Weft-Replenishing Looms, of which the following 10 is a specification.

Our invention relates to a filling thread cutting mechanism for weft replenishing looms, which is adapted to cut the filling thread on the substantially exhausted bobbin which is to be removed from the active 15 shuttle, and to hold the end of the filling thread which extends from the cutting mechanism to the selvage of the woven fabric, to cause it to engage the filling fork 20 and move it into an inoperative position, to prevent the stopping of the loom.

The object of our invention is to provide a filling thread cutting mechanism of simple construction, which is adapted to be applied to and used on looms of the class referred to, and preferably connected with and put into operative position by some of the parts of the transferring mechanism on the magazine, which may be of any usual 30 and well known construction.

Our invention consists in certain novel features of construction of our improvements as will be hereinafter fully described.

We have only shown in the drawings our 35 improved filling thread cutting mechanism, combined with some of the parts of a loom, sufficient to enable those skilled in the art to understand the construction and operation thereof.

Referring to the drawings: Figure 1 is a 40 section, on line 1, 1, Fig. 2, looking in the direction of arrow *a* same figure, showing our improvements in filling thread cutting mechanism, combined with the breast beam, and the lay of a loom. Fig. 2 is a plan view 45 of the parts shown in Fig. 1, looking in the direction of arrow *b*, same figure. The broken lines represent the filling fork slide, and filling fork, which is engaged by the filling thread; these parts are not shown in 50 the other figures. Fig. 3 is a section, on line 3, 3, Fig. 2, looking in the direction of

arrow *c*, same figure, and, Fig. 4 corresponds to Fig. 3, but shows the thread cutting mechanism in its operative position. 55

In the accompanying drawings, 1 is the breast beam, 2 the lay, 3 the reed, and 4 the hand rail, Figs. 3 and 4.

5. see Fig. 2, is the end of a shuttle box, with a shuttle 6 therein, from which the 60 filling thread 6' extends to the selvage of the woven fabric, not shown. The stand 7 of the feeler fork slide, carrying the feeler fork, shown by broken lines in Fig. 2, is mounted on the breast beam, and has in this 65 instance secured thereto by bolts 8', a stand 8, which is provided with bosses 8'' and 8''', which are adapted to form bearings for an inwardly extending bar 9. The outer reduced end 9' of the bar 9 is guided in the 70 boss 8''.

A helically coiled expansion spring 10 encircles the reduced portion 9', and bears at one end against the boss 8'', and at its other end against the enlarged portion of 75 the bar 9. A key 11 is secured by a screw 12 to the boss 8''', and enters a groove 9'' in the bar 9, which in this instance is slidingly held within the boss 8'''. The key 11 prevents the bar 9 from rotating or turning. The expansion spring 10 acts to move 80 inwardly the bar 9, as shown in Fig. 4, when it is released, until a pin 13, which extends transversely through the bar 9, engages the boss 8''', as shown in Fig. 4. 85

The bar 9 is provided at its inner end with a head portion 9^a, which in this instance extends downwardly and has secured thereto the lower stationary cutting blade 14 of the cutting mechanism. The upper 90 cutting blade 15 is secured to an arm 16, which has its hub 16' pivotally mounted on a stud or bolt 17. The bolt 17 extends through the head portion 9^a, and is secured therein by a nut 18. A spring blade 19 is 95 in this instance adjustably secured at one end, see Figs. 3 and 4, to the head portion 9^a, by the nut 18. Said spring blade 19 extends downwardly and below the head portion 9^a, and then upwardly again and on 100 the opposite side, as shown at 19', Fig. 1. The end 19' of the spring 19 is adapted to yieldingly engage the lower surface of a longitudinally extending projection 16'' on

the arm 16, and form a clamping and holding device for the cut end of the filling thread 6', extending from the selvage of the woven fabric, as shown in Fig. 2.

5 A helically coiled contraction spring 20 has one end connected to a lug 16'' on the arm 16, see Figs. 1 and 2, and its other end to a lug 9'' on the head 9^a, and acts to open the cutting jaws, as shown in Fig. 4, when 10 the arm 16 is released, as hereinafter described. Extending downwardly from the hub 16' of the arm 16, is an arm 16^a; the lower end of said arm 16^a is provided with a notched portion 16^a', which is adapted to 15 be engaged by the notched end 21' of an arm 21, which has its hub 21'', see Fig. 2, pivotally mounted on a stud 22 on a stand 23. A helically coiled torsion spring 24, see Fig. 2, which has one end connected to a 20 collar 25, fast on the stud 22, and its other end connected to the hub 21'' of the lever 21, acts to yieldingly move upwardly the arm 21, to the position shown in Fig. 3, to engage the notched end 16^a' of the lever 25 16^a, and hold the cutting mechanism in its inoperative position. The second arm 21'' on the lever 21, has a stud 21''' thereon, which extends loosely in a slot 26' in the rod head 26, which is adjustably connected to 30 the lower end of a vertically extending rod or wire 27. The upper end of the wire 27 has connected thereto operating means, not shown, preferably on the transerrer mechanism on the magazine, not shown, which 35 may be of any usual construction. The operating means cause, upon the practical exhaustion of a bobbin, the arm 21''', through the upward movement of the wire 27, to operate and move the lever 21, from the 40 position shown in Fig. 3, to the position shown in Fig. 4, to release the arm 16^a, and allow the expansion spring 10, to move the cutting mechanism forwardly and toward the lay, as shown in Fig. 4. The end of the 45 lever 21 has a cam-shaped or curved projection 21^a thereon, which is adapted as the lay moves forward, to engage the free end of a curved shaped wire 28, see Fig. 4, to move downwardly said wire, as shown in 50 said Fig. 4. The other end of the wire 28 is secured by a screw 29' in a lug 29'' on a collar 29, which in this instance is loosely mounted on the protector rod 30. A second wire 31 is secured at one end by a screw 31' 55 in a lug 31'' on a collar 31''', which in this instance is loosely mounted on the protector rod 30. The wire 31 has its upper end bent rearwardly and extending toward the reed, see Fig. 3. The wire 31 is located within a 60 groove or recess in the upper side of the lay, and has its extreme end bent upwardly to form a hook 31^a, which on the upward movement of the wire 31, as shown in Fig. 4, engages the filling 6' to carry it between 65 the open blades of the cutting mechanism.

The two collars 29 and 31''' have cam shaped engaging surfaces on their contiguous ends, as shown in Fig. 2, and are held in yielding engagement with each other, to move as one collar, or to allow one collar to 70 move independently of the other, by a helically coiled expansion and torsion spring 32, see Fig. 2, which encircles the protector rod 30 and has one end connected to a collar 33, secured on the rod 30 by a screw 33', and its other end connected to the collar 31'''. The 75 spring 32 acts to hold the two collars 29 and 31''' in yielding engagement with each other, to move as one collar, and also acts to rotate said collars on the protector rod 30, 80 to return the wires 28 and 31 to their normal position, shown in Fig. 3.

By means of the interlocking collars 29 and 31''', and the spring 32, forming a give-way connection, if a shuttle extends above 85 the wire 31, and prevents the raising of said wire, the collar 29, rotated by the downward movement of the wire 28, engaged by the end 21^a on the lever 21, as the lay moves forward, will engage and move the collar 31''' 90 longitudinally on the shaft 30 against the action of the spring 32 and allowing the wire 31 to remain stationary without any breakage of the parts.

When in the operation of the loom, the 95 feeler detector mechanism indicates for a change of filling, through the rod or wire 27, the lever 21 is moved downwardly, as shown in Fig. 4, and disconnected from the lever 16^a of the cutting mechanism, allowing the 100 cutting mechanism, through the spring 10, to be moved to its forward position, and the spring 20 to raise the arm 16, carrying the cutter blade 15, and as the lay moves forward, the engagement of the wire 28 with 105 the cam-shaped end 21^a on the lever 21, rocks the collars 31''' and 29 on the rod 30, against the action of the spring 32, and raises the hooked end 31^a on the wire 31, to cause it to engage and positively carry the 110 filling 6' between the open jaws of the cutting mechanism. The continued forward movement of the lay causes the projection 34 thereon to engage the arm 16^a, see Fig. 3, and causes the arm 16 carrying the cutting 115 blade 15 to close and sever the filling thread 6' extending between the cutting blades, as shown in Fig. 2, and also to clamp and hold between the projection 16'' and the end 19' of the spring 19, the end of the filling thread 120 6', extending from the selvage of the fabric. The taut filling thread, as the lay moves forward, will engage the filling fork of the side filling fork stop motion, shown by broken lines in Fig. 2, and tilt said fork, and hold it in its inoperative position to prevent the stopping of the loom. On the extreme forward movement of the lay, the cutting mechanism is moved rearwardly to its inoperative 125 position, and the arm 16^a is engaged by the 130

lever 21, moved upwardly by the spring 24, and held by said lever, as shown in Figs. 1 and 3.

It will be understood that the details of 5 construction of our improvements may be varied if desired.

Having thus described our invention, what we claim as new and desire to secure by Letters Patent is:

- 10 1. In a filling thread cutting mechanism for weft replenishing looms, two cutting blades mounted on a movable member, and said member, movable toward and away from the lay, a spring for moving said member and blades into operative position, means to close said blades, to sever the filling thread, and to carry said member and blades into an inoperative position, means to lock 15 said member and blades in said inoperative position, against the action of said spring, and automatic means to release said member and blades, to allow them to move into operative position, and yielding means, to engage and carry the filling thread between 20 said blades.

2. In a filling thread cutting mechanism for weft replenishing looms, two cutting blades mounted on a movable member, and said member, movable toward and away from the lay, a spring for moving said member and blades into operative position, 30 means to close said blades, to sever the filling thread and to carry said member and blades into an inoperative position, means to lock said member and blades in an inoperative position, against the action of said spring, and automatic means to release said member and blades, to allow them to move into operative position, and a device to engage and carry the filling thread between 35 said blades, said device connected with and operated through a give-way connection, to allow said device to remain stationary and prevent breakage.
